BOILER

Curt Negendank, Mellendorf, Germany, assignor
to Schmidt'sche Heissdampf - Gesellschaft,
m. b. H., Kassel-Wilhelmshöhe, Germany

Application October 21, 1932, Serial No. 638,886,
and in Germany December 2, 1931

2 Claims. (Cl. 257—239)

The heat delivering structures used in indirect-
ly heated high pressure heat exchangers com-
monly comprise manifolds or headers and tubu-
lar elements whose ends are expanded into them.
5 These structures lie entirely within the drum in
which the steam for use is to be generated and
communicate with the remaining part of the cir-
cuit for the heat carrier by means of portions
extending through the drum wall. This arrange-
10 ment has proved entirely practical in use. The
heating structures must, however, be taken out
of the drum in case leaks occur and a re-expand-
ing of the ends of the tubular portions is re-
quired. In order to obviate this inconvenience,
15 the headers have at times been arranged outside
of the drum. They have in such cases been given
the form of a lid or cover forming a closure for
the opening in the end of the drum and have been
secured to the end of the drum by means of studs
20 or bolts. In practice, it has proved very difficult
to keep the joint between the cover and the end
of the drum tight. Leakage has especially ap-
peared when the drum was first heated up and
is due mainly to the fact that the header is heated
25 more by the heating steam, which has higher
temperature than the contents of the drum, than
the wall of the drum and therefore expands more.
This results in a permanent elongation of the
studs or bolts so that upon cooling, the tension
30 of the bolts is insufficient to keep the joint tight.
It is therefore necessary each time before the
drum is heated up to pull up on the stud nuts
thereby subjecting these bolts and the joint to
severe usage.
35 By the present invention this difficulty is
avoided and at the same time the advantage is
retained that the rolled joints of the tubes are
accessible from the outside.

The invention consists in having the drum clo-
40 sure seat from the inside against the opening
in the drum, much like a manhole closure, and
having the rolled joints for the tubes all inside
of the drum opening. The means for securing
45 this header are not subjected to stresses by the
differential expansions of the header and the
drum wall when heated up, since the interior
pressure in the drum keeps the cover tight on
its seat. The rolled joints are readily accessible
50 through the end opening of the drum and, com-
pared with the arrangement having the headers
outside of the drum, there is the further advan-
tage that the loss through heat radiation is re-
duced.

The drawing shows an illustrative example of
55 the inventive idea. Fig. 1 shows a longitudinal

section through the boiler drum; Fig. 2 shows,
on an enlarged scale, a front view of the drum;
Fig. 3, a vertical section on line 3—3 of Fig. 2;
Fig. 4, a vertical section on line 4—4 of Fig. 2,
and Fig. 5 a fragmentary section on line 5—5 of
Fig. 3.

The drum 1 is provided at the one end with an
opening 2 and at the opposite end with an open-
ing 3. Inside of the drum lies a heat delivering
body consisting of the cover-shaped header or
60 collector 4 and harpin-shaped heating tubes 5.
The collector or header 4 is seated from the in-
side against the opening 2 like a manhole cover.
The opening 3 at the opposite end of the drum
is larger than the opening 2 by such an amount
65 that the entire heat delivering body including
the header 4 can be introduced into the drum from
this end. The opening 3 is closed in the usual
manner by the cover 6. The header 4 which
closes the opening 2 is secured by means of yokes
70 which engage the end of the drum, studs 8
which are secured to the header 4 and extend
through openings in the yokes 7, and nuts 9 en-
gaging the yokes on their outer side. The header
is made out of a solid block of steel or other suit-
75 able material. It has formed in it by any desired
means two large bores extending inwardly from
one side 12, into which are screwed or other-
wise secured the two nipples 14 and 15, extending
80 outwardly through opening 2 and equipped with
connecting means such as flanges 16—16. One
of these nipples supplies and the other removes
the heating medium. Extending inwardly from
85 the other side 10 of the header are holes into
which are secured the pipes 5. These holes are
arranged in rows and extend entirely through
the block of steel or into the space within the
nipples 14 and 15. Those which extend entirely
90 through the block are plugged in any suitable
manner as e. g. by the rolled plugs 13 after the
tubes 5 have been rolled in. For those holes open-
ing directly into the nipples 14 and 15 no closures
at their outer ends are required. Transverse pas-
95 sages 17 connect those of the holes not falling
within the contour of the nipples with the in-
terior of the nipples either directly or via the
vertical connecting passages 18. The outer ends
100 of these passages 17 and 18 are also suitably
plugged. The nipples 14 and 15 are secured in
place before the passages opening laterally into
105 them are drilled.

What I claim is:

1. In apparatus of the class described, the
combination of a drum having an opening in its
wall with a seat surrounding the opening on the

110

inside of the drum, a header engaging the seat and forming a closure for the opening, U-shaped tubes within the drum and having their ends expanded into the header, the header being provided with access openings opposite the tube ends through which expanding tools can be inserted, and closures for said access openings, said access openings lying within the area of the opening of the drum so as to be accessible from the outside of the drum.

2. Apparatus in accordance with claim 1, the said opening being in one end of the drum, and the drum being further provided with an opening at the opposite end large enough to permit the insertion and removal of said header and tubes as a unit, the apparatus further comprising a closure for said second opening.
